UNITED STATES PATENT OFFICE.

HOWARD E. CRAFT, OF SPRINGFIELD, MASSACHUSETTS.

DISPLAY SIGN.

Application filed April 8, 1927. Serial No. 182,102.

This invention relates to improvements in display signs and more particularly to the type commonly known as side walk signs.

One object of the invention is the provision of a sign that is simple in construction and light in weight to the end that it may be manufactured cheaply.

Another object is the provision of a sign which has pivoted frame members that are adapted to be readily moved between open and closed clamping positions to facilitate the exchanging of sign plaques as frequently as may be desired.

Other objects and advantages will be apparent from the following description of the invention which is illustrated in the form at present preferred by means of the accompanying drawings in which:

Fig. 1 is a perspective view showing the side frames in closed position and clamping a sign plaque therebetween;

Fig. 2 is an end elevational view showing the frames in an open position ready to receive a sign plaque; and

Fig. 3 is a cross sectional view on the line 3-3 of Fig. 1.

Referring to the drawings in detail, 1 and 2 represent side frames each of which comprises a U-shaped frame member having spaced side supports 1', 1' and 2', 2' connected together at the upper ends by cross bars or tie members 1'' and 2''. The frame members are preferably made of angle bars of well known form which, when formed into frames of the shape shown, are turned or arranged so that the corresponding angularly disposed flanges of the bars of one of the frames are disposed in planes corresponding to those of the other frame.

The over-all width of the frame 2 is preferably some less than that of the frame 1 so that it will fit within or nest inside the side flanges of the bars of the frame 1 as shown.

The lower extremities of the members 1' and 2' are preferably arranged in a diverging relation so as to provide spaced supporting feet as shown, and as indicated at 4 the side supports 1' and 1' of the frame 1 are pivoted to the supports 2' and 2' of the support 2 so that the frames 1 and 2 may be swung between open and closed position in Figs. 1 and 2.

A cross tie bar 5 is fixed to or integral with the side supports 1', 1' of the frame 1 and is preferably in the form of an angle

bar which is disposed so as to have a flange 6 extending rearwardly or between said side supports to serve as a support or stop for a sign plaque S.

The sign plaque S may be of any suitable relatively thin material and adapted to carry any desired ornamental or advertising matter and is preferably of such dimensions as will fit between the flange 6 of the member 5 and the corresponding flange of the upper tie member 1'' as well as between the side flanges of the side supports 1' and 1'.

Clamping bolts 8 are provided which pass through suitable registering or aligned openings in the upper tie members 1'' and 2'' and in the upper edge of the sign plaque between the frames and serve to hold the frames 1 and 2 in their closed sign clamping relation as shown in Fig. 1.

Other bolts 9 pass through the member 5 and lower edge of the sign and serve to securely clamp the lower edge of the sign S to the member 5.

By removing the bolts 8 and 9, the frame members 1 and 2 may be opened or swung apart to permit the removal of a sign plaque and the insertion of another as will be readily obvious.

It will be noted that the edges of the sign plaque, which may be unfinished or otherwise roughened and unsightly, are concealed by the nested flanges of the angle bars and that the joints between the edges of the sign plaque and frame members are sealed up so that water is prevented from striking an exposed edge of the sign plaque and running down across the face thereof.

I am aware that many changes may be made in the form of the invention without departing from the scope thereof, and I prefer therefore to be limited by the appended claims rather than by the foregoing description.

What I claim is:

1. A display sign comprising in combination, a pair of frame members each formed of angle bars and having side supports connected by a cross bar at the upper ends thereof, the flanges of the angle bars of one frame being disposed in planes corresponding to the planes of the flanges of the other so that one of said frames may be nested within the other and the lower extremities of the supports of one frame being disposed in a diverging relation with respect to those of the other, pivotal connections between the sup-

ports of the frame members to permit a relative opening and closing movement of said frames, a cross bar fixed to and extending between the supports of one frame member 5 disposed intermediate the ends of said supports and having a transverse flange disposed in the space between the side supports of the frames to serve as a support for a sign plaque, a sign plaque for insertion 10 between the flanges of the nested portions of the frame angle bars, and means associated with said frames for holding them in a closed and nested plaque clamping relation.

2. A display sign comprising in combination, a pair of U-shaped frame members of

angle bars having flanges disposed so that the flanges of one are disposed parallel to those of the other and one frame being smaller than the other so as to nest therein, the side bars of said frames being hinged 20 together intermediate their ends and the ends of the bars of one frame diverging from the ends of the bars of the other so as to permit a hinging action of the frames whereby they may open or close with respect to one 25 another above said hinge connection.

In testimony whereof I have affixed my signature.

HOWARD E. CRAFT.
